CAGE AND CARTRIDGE ASSEMBLY FOR INVERTIBLE FIRE EXTINGUISHER

Charles K. Huthsing, Jr., Culver City, Calif.

Application September 27, 1955, Serial No. 536,841

3 Claims. (Cl. 169—31)

This invention relates generally to an improved structure for a cartridge and tubular cage assembly in an invertible type fire extinguisher, and more particularly to a means of increasing the kinetic energy in the cartridge as it moves towards a puncture pin in the extinguisher in response to rotation of the extinguisher from a normal, upright position to an inverted position.

In a conventional type invertible fire extinguisher, a tubular cage is axially disposed within the body of the extinguisher and extends downwardly from the collar or tank outlet end. The cage is closed at both ends and a sealed cartridge is disposed within the cage for movement from the lower end to the upper end, in response to rotation of the extinguisher from its normal upright position to an inverted position.

In order to break the seal of the cartridge, a puncture pin is secured to the upper end of the cage so that, upon rotation of the extinguisher, the seal of the cartridge will be ruptured by impact with the puncture pin after accelerated movement of the cartridge from the lower end of the cage to the upper end of the cage.

The problem with this type of cage and cartridge assembly has been to provide sufficient kinetic energy in the cartridge, as it moves in response to rotation of the extinguisher, to result in the requisite force necessary to break the seal of the cartridge when it comes in contact with the puncture pin. This problem is particularly troublesome where the cartridge must be designed to contain a gaseous fluid (for example, carbon dioxide) under extremely high pressure with the consequences that the seal must be correspondingly designed to have high strength characteristics. In certain applications, therefore, in order to rupture the seal when it comes in contact with the puncture pin the cartridge must be moving at a relatively high velocity.

The problem has been avoided, although not actually solved, in some extinguisher designs by using an external manual means of forcing the puncture pin through the cartridge instead of depending upon the movement of the cartridge itself to bring about the necessary force. The use of an external means, however, requires additional parts as well as an increased expense in the manufacture of the extinguisher, and further has the disadvantage of providing an additional operating step before the extinguisher is ready for operation.

It is, therefore, an object of the present invention to provide an improved cartridge and cage assembly for an invertible type fire extinguisher in which sufficient kinetic energy may be imparted to the cartridge as the extinguisher is inverted, whereby a positive and effective puncturing of the cartridge seal will result.

Another object of the present invention is to provide a cartridge and cage assembly according to the previous object in which the modifications necessary to existing invertible extinguisher designs is of such a limited nature that the embodiment of the invention in such extinguishers will not appreciably affect the overall manufacturing costs.

A still further object is to provide an improved cage

tube and cartridge assembly for an invertible type fire extinguisher, in which no external application of force is required to break the seal in the cartridge.

These and other objects and advantages of the present invention are attained by providing a cage tube designed to have a flared out portion so as to form an increased diameter section. The cartridge disposed in the cage for vertical movement is correspondingly modified to include a coupled annular member adapted to be axially disposed within said increased diameter section when the extinguisher is in its upright position. As the extinguisher is rotated to its inverted position, the annular member is adapted to engage the flared out portion so as to restrain movement of the cartridge towards the upper end of the cage tube assembly until the extinguisher is in a given angular position.

The flared out portion of the cage tube and the annular member coupled to the cartridge are relatively sloped such that the cartridge will slide free of the flared portion when the extinguisher is rotated to the given angular position. In practice, an angle of twenty to forty-five degrees from the vertical is attained through the engagement of the annular member with the flared out portion of the cage tube before the cartridge is actuated downwardly towards the puncture pin. As a consequence, it will be evident that the cartridge, when the cage tube is disposed at twenty to forty-five degrees from the vertical, will be relatively positioned a greater distance from the puncture pin to thereby have an increased potential energy. As a consequence, an appreciably larger kinetic energy will be imparted to the cartridge.

A better understanding of the present invention will be had by reference to the accompanying drawings, in which preferred embodiments are shown for illustrative purposes, and in which:

Figure 1 is a partial cross sectional view of the upper portion of a typical, invertible type fire extinguisher with the improved cartridge and cage tube assembly of the present invention provided therein;

Figure 2 is a view of the cartridge and cage tube assembly in the angular position immediately before the cartridge is about to be freed for actuation towards the puncture pin;

Figure 3 is a top view of the cartridge;

Figure 4 is an enlarged view of the encircled portion 4—4 of Figure 3; and

Figure 5 is a partial cross sectional view of the cage tube illustrating a modified form of the present invention.

There is shown in Figure 1 the upper portion of a fire extinguisher 10 having a threaded collar 11 on which is mounted a wheel cap 12.

Vertically disposed within the extinguisher 10 is a cage tube 13 having an annular flange 14 near its upper end and dimensioned so as to be supported on a recessed section 15 on a collar 11. The cage tube 13 is provided with an upper end closure 16 to which is secured a downwardly extending puncture pin 17. According to a primary feature of the present invention, the cage tube 13 is flared out for its given diameter to form an increased diameter section in the form of a bead 18. The cage tube 13 is further provided with a lower end closure 19, which is adapted to support a cartridge 20 within the tube when the extinguisher 10 is in an upright position.

The cartridge 20, as such, is of a conventional design and is adapted, for example, to contain a compressed gas such as carbon dioxide. The cartridge has a sealed end 21 to be ruptured when the cartridge 20 comes in contact with the puncture pin 17. As another important part of the present invention, the cartridge has coupled near its sealed end 21 an annular member in the form of a pilot ring 22, shown more clearly in the view of Figure 2. The pilot ring 22 has a plurality of circular

apertures 23; the apertures 23 are disposed within the ring 22 to decrease the air resistance the ring offers to movement of the cartridge 20 as it travels through the cage tube 13 towards the puncture pin 17.

The co-operative function of the bead 18 and the pilot ring 22 in effecting a more positive rupturing of the sealed end 21 by the puncture pin 17 will now be described. The extinguisher 10 is normally disposed in the upright position indicated by Figure 1. When the extinguisher is to be operated, it is turned upside down to an inverted position, as by rotation in the direction of the arrow 24 in Figure 1. As the extinguisher 10 is rotated, the cartridge 20 will fall against the side walls of the cage tube 13, and similarly the pilot ring 22 will move radially in one direction to contact the bead 18. Through the first ninety degrees of rotation, the cartridge 20 will always have a component of force, as a result of its weight, acting towards the lower end closure 19 and preventing the cartridge from sliding towards the upper end closure 16. However, after the extinguisher has been rotated ninety degrees, further rotation will result in a component of force from the weight of the cartridge acting in an axial direction, as designated by the arrow A in Figure 2 toward the upper end closure 16.

With a conventional cartridge, as soon as the component of force in the direction of the end 16 overcomes the frictional component of force between the cartridge and the side walls of the cage tube 13, the cartridge will begin sliding or slipping towards the closed end 16. The purpose of the present invention is to prevent this slippage from occurring until the extinguisher 10 has reached a given angular position, wherein the cartridge and cage tube assembly are disposed, as in Figure 3, at approximately a thirty degree angle with respect to the inverted position.

The bead 18 and pilot ring 22 function together as a means of causing this delayed movement. As shown more clearly in the view of Figure 4, the bead 18 includes an arcuate portion 26 having a slope adapted to engage and carry the whole weight of the cartridge 20. When the inclination of the extinguisher 10 exceeds a given value relative to the slope of the arcuate portion 25, the pilot ring will slip off the portion 25. In other words, before the cartridge may begin moving towards the puncture pin 17, the extinguisher must be inclined to a position such that at the point of engagement between the edge of the pilot ring 22 and the portion 25, there is a component of force from the weight of the cartridge acting axially towards the puncture pin.

By delaying movement of the cartridge 20 until the extinguisher has been rotated 150°, for example, to the angular position of Figure 3, the cartridge 20 is disposed so that it will have a substantially increased kinetic energy at the time it impacts the puncture pin. This results from the fact that the cartridge 20 will be held at its initial vertical distance from the puncture pin 17 until a greater weight component A is provided, and also from the fact that a smaller component of the weight as represented by the arrow N in Figure 2 of the cartridge will be acting normal to the side walls of the cage tube 13, thereby decreasing the proportional retarding frictional force with the side walls tending to prevent acceleration of the cartridge 20 towards the puncture pin. Although the optimum condition would be to have the cartridge 20 disposed in a true vertical position before beginning movement, it has been found in practice that an angle of

twenty to forty-five degrees with respect to the vertical imparts sufficient kinetic energy to the cartridge 20 to rupture the sealed end 21 as it impacts the pin 17. Of course, the necessary angle required will vary to a certain extent according to the strength of the sealed end 21, the length of the cage tube 13, and other similar design considerations.

After the cartridge 20 impacts the puncture pin 17 to break the sealed end 21, the pressurized gases within the cartridge will escape and pass out of the cage 13, as through an aperture 26 in the side walls of the cage.

In Figure 5 there is shown a modification to the improvement in the cage tube construction. In this view, instead of providing a bead 18 as in Figure 1, a cage tube 27 is shown as having a flared section 28 extending outwardly into an increased diameter section of the cage tube 27. The flared out section 28 is equivalent to the use of the bead 18 since one arcuate portion 29 of the bead, as seen in Figure 4, does not actually function as a part of the invention, but rather only the portion 25 as discussed previously. The bead 18 is used in a preferred construction since it is adaptable to embodiment in the cage tube 13 at a lower manufacturing cost.

It will thus be apparent that the improved cartridge and cage tube assembly of the present invention functions as an automatic means of providing the requisite force in an invertible type fire extinguisher to assure a positive puncturing of the seal within the cartridge. Although the drawings show preferred embodiments, it is apparent that changes and modifications may be made with respect to the flared out section and the corresponding design of the pilot ring without departing from the spirit and scope of the invention.

What is claimed is:

1. In a fire extinguisher operable by rotation from an upright position to an inverted position, the combination comprising: a cage tube vertically supported in said extinguisher, said tube having a lower end closure, and an upper end closure with a puncture pin secured thereto and extending downwardly into said tube, and said tube additionally having a flared out portion said flared out portion being inclined with respect to a plane normal to the axis of said tube and forming an increased diameter section; a cartridge supported within said tube on said lower end closure, and adapted to move toward said upper end closure in response to rotation of said extinguisher from said upright position to said inverted position, said cartridge having a coupled annular member spaced from and positioned in opposing relationship to said flared out portion, said annular member being dimensioned to frictionally engage said flared out portion and restrain said cartridge from movement towards said upper end closure in response to said rotation until said extinguisher is disposed within at least 45° of said inverted position.

2. The combination according to claim 1, in which said tube is provided with a bead to define said flared out portion.

3. The combination according to claim 1, in which said annular member is provided with a plurality of apertures.
